DESIGN FOR A COMBINED DRINK STIRRER AND PICK

George W. Bergen, West Belmar, and Robert B.
Dabney, Manasquan, N. J.

Application November 17, 1937, Serial No. 72,956

Term of patent 3½ years

To all whom it may concern:

Be it known that we, George W. Bergen and Robert B. Dabney, citizens of the United States, respectively, residing at West Belmar and at Manasquan, in the county of Monmouth and State of New Jersey, have invented a new, original, and ornamental Design for a Combined Drink Stirrer and Pick, of which the following is a specification, reference being had to the accompanying drawing, forming part thereof.

In said drawing, Fig. 1 is a side face view, and Fig. 2 is an edge elevation of a combined drink stirrer and pick, showing our new design.

We claim:

The ornamental design for a combined drink stirrer and pick, as shown.

GEORGE W. BERGEN.
ROBERT B. DABNEY.
